DESIGN FOR A COMBINED MANICURE STAND AND LAMP

Ezio Scateni, Chicago, Ill.

Application August 6, 1941, Serial No. 102,712

Term of patent 3½ years

To all whom it may concern:

Be it known that I, Ezio Scateni, a citizen of the United States, residing at Chicago, in the county of Cook and State of Illinois, have invented a new, original, and ornamental Design for a Combined Manicure Stand and Lamp, of which the following is a specification, reference being had to the accompanying drawing, forming a part thereof.

Fig. 1 is a perspective view of a combined manicure stand and lamp embodying my new design.

Fig. 2 is a top plan view of the base of the stand shown in Fig. 1.

I claim:

The ornamental design for a combined manicure stand and lamp, substantially as shown.

EZIO SCATENI.
